UNITED STATES PATENT OFFICE.

FRANK H. LEHMAN, OF LEBANON, PENNSYLVANIA.

ASH-RECEIVING DEVICE.

1,283,822.

Specification of Letters Patent.

Patented Nov. 5, 1918.

Application filed November 26, 1917. Serial No. 203,999.

To all whom it may concern:

Be it known that I, FRANK H. LEHMAN, a citizen of the United States, residing in Lebanon, in the county of Lebanon and State of Pennsylvania, have invented certain new and useful Improvements in Ash-Receiving Devices, of which the following is a specification.

My invention relates to ash receiving devices and more particularly to the type or general class of such devices exemplified in my application for Letters Patent, Serial Number 168522, filed May 14, 1917, wherein means are provided for conveying ashes from the ash pit of a house heating furnace into a well or cavity located in front of and adjacent the furnace.

In my said application for Letters Patent, I disclose a well and ash conveying means designed and practically restricted in use to the employment therewith of a single removable ash receptacle. I find, however, that in some cases, a well having a larger storage capacity and adapted to accommodate a plurality of removable receptacles instead of one, is desirable, since a well of this kind is capable of being more economically emptied and has the additional advantage of requiring less attention.

The object of my present invention therefore is to supply a device of this kind constructed and formed with a view to the use of a plurality of receptacles, and to provide relatively simple and novel means for conducting the ashes into the several receptacles. To this end I provide a well of substantially segmental or circular outline, locating the receptacles therein at points adjacent the outer or circumferential wall, and I mount therein a chute adapted to swivel about a central point with respect to the receptacles, whereby ashes deposited in the chute at such central point may be conveyed radially outward and delivered into any desired one of the several receptacles, thus enabling all of the receptacles to be successively filled. The well is covered by a top plate sunk in flush with the surrounding floor, and the plate is formed with openings having removable covers or doors for the introduction and removal of the receptacles.

Another object of the invention is to provide means for supporting the chute from the top plate in such a manner as to enable the same to be rotated by the application of

a slight force to a rotatable member disposed on the upper surface of the plate.

A further object is to provide suitable means adjacent the openings in the top plate for the erection thereover of a portable hoist such as disclosed in my application for Letters Patent, Serial Number 168523, filed May 14, 1917, to facilitate the removal and replacement of the receptacles.

With the above and other objects in view, the invention consists in the novel features of construction and the combination of parts as hereinafter described, pointed out in the claims, and illustrated in the accompanying drawings, in which,

Figure 1 is a top plan view of my invention;

Fig. 2 a vertical sectional view thereof;

Fig. 3 a sectional view of the top plate on the line 3—3 of Fig. 1;

Fig. 4 a plan view of the rotatable chute supporting disk; and,

Fig. 5 a sectional view of said disk on the line 5—5 of Fig. 4.

Similar letters and numerals of reference indicate corresponding parts throughout the several views.

Referring to the embodiment of the invention shown in the drawings, A represents a well or cavity sunk in the floor in front of a furnace C and adjacent the ash pit D thereof, and E and F represent removable ash receptacles contained in the well. In this instance the well is shown as being approximately semi-circular in plan extending laterally an equal distance on either side of the median line of the furnace and having its straight or diametrical side at right angles to such median line and proximate the ash pit. The well is of sufficient size to accommodate a plurality of the removable receptacles, and the receptacles are arranged therein in spaced relation adjacent the outer or circumferential wall. A top plate 1, resting flush with the surrounding floor, covers the well and is provided with spaced openings as 2 adjacent its outer periphery, said openings being equal in number with the receptacles and the respective openings coinciding with the respective receptacles and being adapted to permit the free passage of the receptacles therethrough. Said openings are adapted to be closed with removable covers, the latter being shown in this instance in the form of hinged doors as 3, piv-

oted to the plate at their inner sides as at 6, and having radial extensions as 7 which enter and overlie suitable recesses as 8 in the margin of the plate, said extensions forming 5 finger pieces for grasping the doors when it is desired to open the same.

- Mounted beneath the top plate so as to swivel in a horizontal plane about a central point or axis with respect to the receptacles 10 is an inclined chute 14 having an inner upward opening or mouth 15 for the reception of the ashes, and being of sufficient length and arranged at an appropriate elevation to swing freely over the receptacles and convey 15 the ashes thereinto. Said chute 14 is preferably mounted for swiveling or rotary movement about said central point or axis by securing the same to a vertical shaft 17 which passes centrally through its mouth 15 and 20 extends upwardly through the top plate, where it is secured to a rotatable member or disk 20 adapted to be operated from the upper surface of the plate. In the construction shown the lower portion 18 of the shaft 25 passes through the bottom of the chute and is bent thereunder to an angle conforming with the inclination of the chute, the latter thus resting thereon and being secured thereto by rivets 19. The rotatable member or 30 disk 20 is set in a circular recess 21 formed in the upper side of the top plate to bring it in flush with the upper surface of the plate, and it carries a central downwardly extending hub 22 which enters an opening 23 in 35 the plate, said hub being provided with a central bore for the reception of the upper end of the shaft. The shaft is conveniently secured to the disk by a cross pin 24, and the disk is provided with means such as radial 40 slots 25 for affording a purchase for the application thereto of any common or handy instrument such as a shovel, rake, poker and other furnace utensil for the purpose of effecting its rotation. Indices as notches 45 26, 27 and 28 in the wall of the recess 21 and a notch 29 on the periphery of the disk are likewise provided to indicate the degree of rotation necessary to bring the chute into the respective positions to cause the delivery of 50 the ashes into the respective receptacles.
- For conducting the ashes from the furnace to the mouth of the rotary chute 14, I employ a stationary chute 39 of approximately the same inclination as the chute 14, having 55 an upper opening or mouth 30 for the initial reception of the ashes and a lower opening or outlet 31, coinciding with the mouth 15 of the chute 14. Said outlet 31 is preferably circular in shape and is provided with 60 a downwardly extending collar or flange 32, and the mouth 15 of the chute 14 is of similar shape with an upwardly extending collar or flange 33 adapted to snugly receive and telescope the flange 32, thus forming an artic 65 ular connection between the chutes which

serves to retain the ashes while at the same time permitting the free rotation of the chute 14. The stationary chute 39 may be secured in position by a bolt as 34 passing through its upper marginal walls and 70 through reinforcing ribs 35 formed on the lower side of the top plate. Preferably the upper or mouth portion 36 of the stationary chute projects outwardly beyond the top plate and extends beneath the ash pit of the 75 furnace, an opening 37 being provided in the bottom or floor of the furnace, through which the ashes may drop directly into the chute.

For removing the receptacles from the 80 well, I preferably employ the improved portable hoist disclosed in my application for Letters Patent, Serial Number 168523, hereinbefore referred to, and for this purpose provide suitable sockets 23 adjacent 85 the openings 2 of the top plate wherein the pivot leg of said hoist is adapted to be inserted, said sockets being adapted to be covered and protected by the doors 3 when the latter are in closed position. 90

It will be clear that, while in the embodiment of the invention shown, the stationary chute 39 extends in part beyond the top plate and underlies the ash pit, said chute may as well be located with its mouth in 95 front of the furnace, so that the ashes may be deposited therein when drawn through the door of the ash pit in the ordinary way. It will likewise be understood that with suitable modifications the device herein described may be employed in connection with a well of circular shape wherein the removable receptacles are arranged about the wall in a complete circle. 100

From the foregoing description of the 105 device, its mode of operation will be fully understood.

While I have in the present instance shown and described the preferred embodiment of the invention, it will be understood 110 that the same is susceptible of modifications in various particulars and of numerous changes in details of construction without departing from its spirit or scope or sacrificing any of its advantages, and it will likewise be understood that it may be employed 115 not only in the handling of ashes but likewise in the accumulation and storage of garbage and other substances.

Having thus described my invention what 120 I claim as new and desire to secure by Letters Patent is:

1. In an ash receiving device, a well, a plurality of removable receptacles disposed adjacent the peripheral wall of the well, a 125 top plate covering the well and having a plurality of openings for the introduction and withdrawal of said removable receptacles, and rotary ash conveying means mounted in the well and operable from the 130

upper surface of the top plate, for receiving ashes at the central region of the well and delivering the same to said receptacles.

2. In an ash receiving device a well of substantially segmental or circular form, a plurality of removable receptacles disposed in the circumferential region of the well, a top plate for covering the well provided with a plurality of openings for the introduction and withdrawal of said removable receptacles, a stationary chute for receiving ashes and conveying the same by gravity to a point above said receptacles in the central region of the well, and an extension chute mounted for horizontal rotary movement about said point and adapted to convey the ashes from said point to said receptacles.

3. In a device of the character described, a well, removable receptacles disposed in the well, and means for conveying ashes from the floor surface to said receptacles, a top plate covering the well and having openings for the introduction and withdrawal of said receptacles, and means disposed adja-

cent said openings for removably erecting 25 thereover a portable hoist to facilitate the withdrawal of said receptacles from the well.

4. In a device of the character described, a well, removable receptacles disposed in the 30 well, and means for conveying ashes by gravity from the floor surface to said receptacles, a top plate covering the well and having openings for the introduction and withdrawal of said receptacles, and socket 35 members located adjacent the periphery of said openings for receiving the pivot member of a portable hoist adapted to be rotatably erected over said openings to facilitate the withdrawal of said receptacles from the 40 well.

In testimony whereof I affix my signature.

FRANK H. LEHMAN.
